UNITED STATES PATENT OFFICE.

WINFIELD E. HINSDALE, OF NEW HAVEN, CONNECTICUT.

DESIGN FOR A SEWER-GAS TRAP.

SPECIFICATION forming part of Design No. 22,606, dated July 11, 1893.

Application filed February 13, 1893. Serial No. 462,204. Term of patent 7 years.

To all whom it may concern:

Be it known that I, WINFIELD E. HINSDALE, a citizen of the United States, residing at New Haven, in the county of New Haven and State of Connecticut, have invented and produced a new and original Design for Sewer-Gas Traps, of which the following is a specification, reference being had to the accompanying drawing, forming a part thereof.

- 10 The drawing is a perspective view of a trap showing the leading features of my design which consist in the octagonal form of the body, having a similarly formed panel on each of its sides and a rectangular panel on the surfaces *a.* and *b.* and panels of the same size and form on each of the surfaces diametrically opposite to *a.* and *b.* and the support for the paneled body consisting of a cylindrical post terminating at its lower extremity in a

circular flange or standard and a similarly formed post at the upper extremity terminating in a similarly formed flange or standard.

What I claim is—

The design for a sewer gas trap herein described, the same comprising the octagonally formed body having an octagonal panel on each of its sides and a rectangular panel on surfaces *a.* and *b.* and panels of the same form on the surfaces diametrically opposite to the surfaces *a.* and *b.* and the cylindrical posts at the upper and lower extremities of the body, each terminating in a circular flange substantially as described and shown in the accompanying drawing.

W. E. HINSDALE.
